UNITED STATES PATENT OFFICE.

JOHN W. CLARK, OF PROVIDENCE, RHODE ISLAND.

RAIL-JOINT STRUCTURE.

Application filed August 2, 1924. Serial No. 729,792.

To all whom it may concern:

Be it known that I, JOHN W. CLARK, a citizen of the United States, residing at Providence, in the county of Providence and

5 State of Rhode Island, have invented certain new and useful Improvements in Rail-Joint Structures, of which the following is a specification.

This invention relates to a rail joint structure adapted to provide a support for meeting rail ends which is carried by the rails themselves and therefore partakes to a considerable extent of the flexibility inherent in the rails whereby the rail structure is permitted 10 to bend slightly at the joint as a heavy load passes thereover and immediately return to its initial position when the load passes.

It has been the practice heretofore in the construction of rail joints to rely upon the fish plates for holding the rail ends in position or to place beneath the meeting rail ends a plate or chair of some form which is firmly supported by the ties or from the roadbed. When the fish plates are relied upon for holding the rail ends in place, the great weight of modern trains and locomotives passing thereover places an excessive strain upon the fish plates and causes them to 20 become bent or worn and thus produces excessive play of the rail ends vertically which eventually causes a great degree of vibration as trains pass thereover and may result in the breakage of the rails or the fish plates 25 at the points where the bolts pass therethrough. When a solid plate is placed beneath the rail ends and fixedly supported from the ties or road bed the ends of the rails are driven down against such plate with 30 such force as trains pass thereover that the plate becomes bent or the upper surface worn at which time the plate loses its value and the strain is taken up by the fish plates to the extent that they have capacity to support 35 it as in the case when no supporting plate or chair is used.

One object of the present invention is to overcome the rigidity naturally inherent in the rail joints previously employed and provide 40 a structure of this character wherein the joint is so constructed as to give the same or substantially the same degree of resiliency as that inherent in the rail itself.

by providing a supporting member carried by the rail and not subject to the disadvantages of such a support when held by the ties.

Another object of the invention is to provide a device of this character wherein the downward force exerted on the supporting 55 plates by the rail ends will be effective to draw the fish plates into closer and binding engagement with the rail ends and further the drawing of the fish plates into closer binding engagement with the rail ends will 60 exert a force tending to press the supporting member into closer engagement with the under surface of the rail ends.

A further object of the invention is the provision of a rail joint structure comprising 70 a supporting member carried entirely by the meeting rail ends whereby a flexible support is provided for the rail ends which permits the requisite resiliency of movement 75 of the rail ends while insuring a proper degree of support therefor at all times.

Other objects and advantages of the invention relate to certain improved details of construction and methods of operation 80 as will be more fully set forth in the detailed description to follow.

Referring to the drawings:

Fig. 1 is a vertical cross-sectional view showing one form of the rail joint,

Fig. 2 is a side elevational view of the 85 structure shown in Fig. 1,

Fig. 3 is a vertical sectional view of a modified form of the rail joint,

Fig. 4 is a side elevational view of the 90 structure shown in Fig. 3,

Fig. 5 is a vertical sectional view of a further modified form of rail joint, and,

Fig. 6 is a side elevational view of the 95 structure shown in Fig. 5, certain of the parts being broken away to more clearly disclose certain details.

In the accompanying drawings forming a part of the present application Figs. 1 and 2 disclose one form which my improved structure may assume in practice wherein 1 and 100 2 designate adjacent rails and 3 and 4 the ties supporting said rails adjacent to their meeting ends. The rails are each provided with a head portion 5, a web 6 and a base 7. A pair of fish plates 8 and 9 are arranged 105 upon opposite sides of the rails at their

meeting ends, each plate being provided with a shouldered portion 10 fitting against the inclined lower surface of the rail head 5 and a base portion 11 adapted to fit against 5 the upper surface of the rail base 7. Bolts 12 and 13 are passed through the fish plates and the web of each rail at points adjacent to the extremities of each plate, although these bolts may be dispensed with in practice 10 the remaining portions of the joint structure furnishing sufficient support for the rail ends and fish plates to render the use of these bolts unnecessary.

The joint structure comprises, in addition 15 to the fish plates, a supporting member 15 located beneath the meeting ends of the rails and having its upper surface inclined outwardly whereby a raised portion 16 contacts with the central portions of the rail 20 ends as shown in Fig. 1. The supporting member is provided with a downwardly projecting extension 17 and outwardly extending portions 18 and 19 which extend somewhat beyond the side edges of the rail base 25 7. The outwardly extending portions 18 and 19 are cut away as at 20 and 21 to form ears 22 and 23. Oppositely positioned side members 24 and 25 are located upon opposite sides of the meeting rail ends, recesses 30 26 being cut or punched from said side members 24 and 25 for the reception of the ears 22 and 23. A suitable bore is formed extending through the ears 22 and side member 24 for the reception of a pivot bar 27 35 and a similar bore is formed in the ears 23 and side member 25 for the reception of a similar bar 28. In this way the side members 24 and 25 are pivoted to the outwardly extending portions 18 and 19 of the supporting 40 member.

The side member 24 is provided with an upwardly extending curved portion 29 terminating in an inclined rounded tip 30 which fits within an inclined recess 31 45 formed on one face of the fish plate 8 above the central part thereof. In a similar manner the side member 25 is provided with an upwardly extending curved portion 33 terminating in an inclined rounded tip 34 50 which fits within an inclined recess 35 formed on one face of the fish plate 9. The side member 24 is provided with an extension 38 projecting downwardly therefrom, and inclined inwardly somewhat towards 55 the extension 17, and the side member 25 is provided with a similar extension 39 similarly inclined towards the extension 17. A plurality of bolts 40 are threaded in the extension 38 and adapted to bear against the extension 17, inclined recesses 41 being provided on the side of the extension 17 to provide suitable contacts for the rounded ends of the bolts 40 as the extension 38 is moved relative to the extension 17. Similar bolts 60 42 are threaded in the extension 39 and bear

upon inclined recesses 43 similarly formed on the side of the extension 17.

In the present instance three bolts are provided for each of the extensions 38 and 39, but it is to be understood that the number 70 of these bolts may be increased or diminished as desired in practice, and it is believed that one or two bolts for each extension may be found adequate in most instances. Bolts 45 are passed through the 75 upper end of the upwardly extending curved portions 29 and 33 of the side members, the fish plates 8 and 9 and the web portion 6 of the rails, the bolts being so located as to pass through the web portion at a point 80 suitably located intermediate the base and head portions of the rail. The openings 46 formed in the upwardly extending curved portions 29 and 33 for the reception of the bolts 45 are made oblong in a vertical plane 85 to permit a slight downward movement of the upwardly extending portions 29 and 33 as the bolts 40 and 42 are tightened. Nuts 47 are applied to the ends of the bolts 45 90 whereby the desired degree of tension may be applied to the parts through which the bolts are passed.

Plano-convex washers 48 may be interposed between the bolt head and the upwardly extending portion 29 as well as between the nut 47 and the upwardly extending portion 33 in the case of each bolt in order to permit slight rocking of the side members and at the same time provide a proper bearing for drawing the parts together in all positions of the side members although any other suitable or desired means may be employed for this purpose. These bolts 45 are not regarded as essential under all conditions and may be employed or dispensed with entirely as may be found expedient in practice. The rounded inclined tips 30 and 34 which fit in inclined recesses 31 and 35 respectively exert a drawing action when the bolts 40 and 42 are tightened 100 tending to draw the supporting member upwardly to force the portion 16 against the central portion of the rail ends. Thus continued tightening of the bolts 40 and 42 105 force the fish plates together and at the same time draw the supporting member upwardly into firm engagement with the lower surface 110 of the rail ends.

If desired, suitable swiveled blocks may be carried by the bolts 40 and 42 to insure 115 proper contact with the extension 17.

The construction therefore provides a rail joint structure having a supporting member for supporting the rail ends which is carried entirely by the rails themselves thus 123 forming a joint structure which acts as a unit with the rail and permits a high degree of flexibility while at the same time preventing independent movement of the rail ends. The heavy construction of the 130

joint amply supports the meeting rail ends, while the fact that the same is independent of the ties or road-bed permits the required degree of resiliency of the rail at the joint 5 without the danger of distortion or breakage.

In the form of the invention illustrated in Fig. 3 and 4 the rails and fish plates are similar to those shown in Figs. 1 and 2, except that the outer faces 52 of the fish plates are plane and are engaged by the plane faces 53 of the upwardly extending portions 54 of the side member 55. The supporting member 56 is formed in this case 15 with a thickened central portion 57 and downward extensions 58 projecting downwardly from points adjacent to the edge of the rail base 7. The supporting member 56 has a raised central portion 60 on its upper 20 face which contacts with the central portion of the rail base from which the upper surface inclines downwardly towards the edges of the rail base. The supporting member extends outwardly beyond the rail base 25 on each side thereof and terminates in ears 61 which fit into openings 62 formed in the side members 55. A pivot bar 63 is passed through openings suitable formed in the ears 61 and side members 55 whereby the 30 side members 55 are pivotally secured to the opposite sides of the supporting member 56 to pivot about the pivot bar 63. Each of the side members 55 is provided with a downward extension 64, each extension being so 35 formed as to be inclined inwardly slightly towards the corresponding downward extension 58 with which it cooperates through the intermediacy of bolts 65 to force the plane faces of the upwardly extending portions 54 of the side members 55 into gripping 40 engagement with the side faces of the fish plates and thereby force the supporting member 56 into close contact with the base of the meeting rail ends. The downward extensions 58 are provided upon their outer 45 faces with rounded depressions 66 to provide suitable bearing surfaces for the ends of the bolts 65 in all positions of the parts. Bolts 67 are provided for securing the ends 50 of the fish plates together through the rail web and for placing the same under suitable tension, although these bolts may be omitted if desired in practice and the fish plates placed under sufficient tension by reason of 55 the force exerted thereon by the upwardly extending portions of the side members alone when the bolts 65 are tightened sufficiently to exert the necessary pressure on the fish plates. It will be obvious that pressure exerted by side members 55 on the fish plates 60 will result in drawing the supporting member 56 upwardly into binding engagement with the base portions of the meeting rail ends thereby providing a support for the 65 meeting rail ends which is carried entirely

by the rails themselves whereby a support is provided which is substantially unitary with the rails and produces substantially the same effect at the joint as would be produced by a continuous rail. 70

In the modified form of the invention shown in Figs. 5 and 6 of the drawings the fish plates 70, lying on opposite sides of the meeting ends of the rails 1 and 2, are of similar construction and are each provided 75 on the lower side with an inturned lug 71 which extends beneath the edge of the base portion 7 of the rail. A supporting member 72 underlies the meeting ends of the rails and is provided on its upper face with a raised portion 73 which bears beneath the central portion of the rail base, and grooves 74 for the reception of the lugs 71. 80

Horizontal extensions 75 project outwardly from the supporting member in substantially the same plane therewith for a purpose which will be more fully described herein-after, and slots 76 are cut in the supporting member for the reception of ears 77 carried by the side members 78. Registering openings 85 are suitably formed in the supporting member 72 and ears 77 for the reception of bars 79 for pivotally mounting each side member on the supporting member and upon opposite sides of the meeting rail ends. Each of the side members 78 is provided with a curved upwardly extending arm 80 provided with a rounded extremity 81 substantially fitting within a suitable rounded depression 82 formed on the outer face of each of the fish plates 70. The side members 78 are each provided with a horizontal extension 83 which projects outwardly and inclined slightly with respect to one of the extensions 75, and bolts 84 are threaded in each of the extensions 83 for contact with the corresponding extension 75 whereby the upwardly extending portions of the side members may be drawn into tensioned engagement with the fish plates and at the same time the supporting members may be drawn upwardly into firm contact with the base portions of the rail ends. The ends of the bolts 84 fit in rounded depressions 85 formed in one surface of the extensions 75 whereby a suitable bearing 115 will be provided for the bolt ends in all positions of the parts. 120

Bolts 86 may be passed through the fish plates 70 and the rail webs adjacent the ends of the fish plates as a further means for clamping the fish plates to the rails or these bolts may be dispensed with if desired in practice and the clamping action of the side members 78 relied upon to exert sufficient tension upon the fish plates for properly clamping them against the sides of the rail ends. As in the previous constructions the number of bolts 84 carried by the extensions for tensioning the parts of the joint structure may be increased or diminished as desired 130

and it may well be found that two bolts will be sufficient to serve for tensioning each side member.

In each of the modified forms of the invention a different mode of contact for the upwardly extending portions of the side members with the fish plates is disclosed and it is to be understood that either of these forms of contact may be employed as may be desired and that too in connection with whichever form of supporting member may prove most desirable under varying conditions of use.

The bolts 45 shown in connection with that form of the invention illustrated in Figs. 1 and 2 of the drawings may or may not be used in connection with the structure shown in Figs. 1 and 2, and, likewise these bolts may be employed, if desired, in connection with the structures shown in Figs. 3, 4, 5 and 6.

The form of fish plates as shown in Figs. 5 and 6 may also be employed, if desired, with the rail joint structure as shown in Figs. 1 to 4 inclusive, and the various structural details as shown in the several modified forms may be employed when practicable with the general joint structure of each of the other forms.

While bolts 40 and 42 have been shown in Figs. 1 and 2 as carried by the extensions 38 and 39 and bearing against the extension 17 to tension the elements of the joint, and similar bolts shown in the modified forms of the invention for performing a similar function, it is to be understood that any other suitable or desired means may be employed for tensioning the structures, such, for example, as suitable wedging means, or other and different arrangements of bolts, as will be apparent to one skilled in the art.

It will be understood by those skilled in the art that the present structure provides a much greater surface for receiving the strain since heretofore the strain has been entirely taken up by that portion of the fish plates bearing against the lower surface of the rail head and the upper surface of the rail base. The present construction provides, in addition to these bearing surfaces bearings beneath the central portions of the rail ends as shown, which bearings are moreover capable of adjustment into forced contact with the rail ends. These bearing surfaces are moreover supported by the rails themselves thus permitting movement with the bending of the rails under the strain of passing trains. The support beneath the meeting rail ends is also in the direct line of the strain taken by the rails, while that taken up by the fish plates is always received at an angle.

It is also within the purview of the present invention to dispense with the fish plates under conditions where this may be prac-

ticable and so construct the upwardly extending portions of the side members that they will properly fit the sides of the rail ends and bear directly thereagainst. In which case bolts may be passed through the upwardly extending portions of the side members and the rail web after the manner shown in Figs. 1 and 2 of the drawings to add strength to the structure and assist in tensioning the same.

What I claim is:

1. In a rail joint structure for clamping meeting rail ends, a supporting member underlying said rail ends, a pair of side members hinged to said supporting member and each provided with a portion extending upwardly into proximity with the rails, and means cooperating with said side members and said supporting member for forcing said side members towards the rails and at the same time drawing said supporting member into closer contact with the under surfaces of said rail ends.

2. In a rail joint structure for meeting rail ends comprising plates positioned on opposite sides of said rail ends, a supporting member underlying said rail ends, a pair of side members each pivotally secured to said supporting member and having a portion extending upwardly into contact with one of said plates, and means for forcing said side members into close contact with said plates and thereby drawing said supporting member upwardly against the under surfaces of said rail ends.

3. In a rail joint structure, a supporting member underlying a pair of meeting rail ends, side members extending upwardly from said supporting member on opposite sides of said rail ends, and means interengaging portions of said side members and said supporting member for positively drawing said supporting member upwardly and forcing the same into close engagement with the under surface of said rail ends adjacent to the longitudinal centers of the rails whereby the said rail ends are flexibly supported from the rails themselves.

4. In a rail joint structure, fish plates overlying the sides of meeting rail ends, a supporting member underlying said rail ends, and means comprising members pivotally connected to said supporting member and engaging said fish plates for forcing said fish plates into gripping engagement with said rail ends and simultaneously positively drawing said supporting member into close engagement with the longitudinal centers of said meeting rail ends to support the same.

5. In a rail joint structure, fish plates overlying the sides of meeting rail ends, a supporting member underlying said rail ends, side members carried by said supporting member and having portions en-

- gaging said fish plates on opposite sides of said rail ends, said supporting member and side members being provided with extensions, and means engaging the said extensions to force the portions of said side members engaging the fish plates into binding contact therewith whereby the fish plates are drawn into clamping engagement with said rail ends.
6. In a rail joint structure, fish plates overlying the sides of meeting rail ends, a supporting member underlying said rail ends, side members carried by said supporting member and having portions engaging said fish plates on opposite sides of said rail ends, said supporting member and side member being provided with extensions, and means engaging the said extensions to force the portions of said side members engaging the fish plates into contact therewith whereby the supporting member is drawn into binding engagement with the under surfaces of said rail ends.
7. In a rail joint structure the combination with the meeting ends of a pair of rails, of plates overlying the meeting rail ends, a supporting member underlying said rail ends, means engaging the said plates on opposite sides of said rail ends, and means for placing said last named means under tension to positively draw said supporting member against the longitudinal centers of said rail ends and thereby provide a support for said rail ends suspended from the rails themselves whereby the jointed portion of said rails possesses substantially the same functions as the solid portion of said rails.
8. In a rail joint structure fish plates overlying the sides of meeting rail ends, a supporting member underlying the meeting rail ends, side members pivotally supported by said supporting member upon opposite sides of said meeting rail ends, extensions projecting from said supporting member and each of said side members and means carried by the extensions on said side members for engaging the extensions on said supporting member whereby said side members may be moved about their pivot points to force portions thereof into gripping engagement with said fish plates.
9. In a rail joint structure the combination with meeting rail ends, of a supporting member therefor carried entirely by the rail ends, side members hingedly connected to said supporting member, and means coacting between portions of said side members and said supporting member whereby said supporting member may be drawn into tensioned engagement with the under surfaces of said meeting rail ends.
10. In a rail joint structure, fish plates overlying the meeting rail ends, a supporting member underlying said meeting rail ends, side members pivotally secured to said supporting member and provided with upwardly extending portions having inclined rounded ends contacting with said fish plates on opposite sides of said rail ends, means extending through said upwardly extending portions, rails and fish plates for drawing the same together, extensions carried by said supporting member and side members, and tensioning means cooperating with the extensions carried by said supporting member and side members whereby the rounded upwardly extending portions of said side members may be forced into close contact with the sides of said fish plates.
11. In a rail joint structure, the combination with meeting rail ends, of a supporting member underlying said meeting rail ends, side members pivotally secured to said supporting member and provided with upwardly extending portions positioned upon opposite sides of said rail ends, extensions carried by said supporting member and said side members, and means cooperating with said extensions for drawing the upwardly extending portions of said side members towards said rail ends and at the same time forcing said supporting member upwardly against the lower face of said rail ends.
12. In a rail joint structure, the combination with meeting rail ends, of a supporting member underlying said rail ends, side members pivotally secured to said supporting member and provided with upwardly extending portions positioned upon opposite sides of said rail ends, bolts extending through the upwardly extending portions of said side members and said meeting rail ends, and means cooperating with portions of said side members and said supporting member for tensioning the elements of the joint structure whereby pressure is exerted upon opposite sides of the rail ends and the supporting member is forced into close engagement with the under surface of said rail ends.
13. In a rail joint structure, the combination with meeting rail ends, of a supporting member underlying said meeting rail ends, side members hingedly connected to said supporting member and having portions extending upwardly upon opposite sides of said rail ends, bolts passed through the upwardly extending portions of said side members and said rail ends, and means independent of said bolts for drawing the said supporting member upwardly into close engagement with the base portion of the rail ends.
14. In a rail joint structure, fish plates overlying the meeting rail ends, a supporting member underlying said meeting rail ends, side members pivotally secured to said supporting member and provided with upwardly extending portions contacting with said fish plates, and bolts passed through the

upwardly extending portions of said side members, fish plates and rails for drawing the said elements together and at the same time forcing the supporting member upwardly into close engagement with the base portions of the rail ends.

15. In a rail joint structure for connecting meeting rail ends, a supporting member underlying said rail ends, a pair of side members pivoted to said supporting member and each provided with a portion extending upwardly from the points of pivotal connection of said side members with said supporting member and into proximity with said rail ends, and means located upon the opposite sides of said pivots from the upstanding portions of said side members for drawing the said supporting member upwardly into tensioned engagement with the under surfaces of said rail ends.

16. In a rail joint structure for connecting meeting rail ends, a supporting member underlying said rails, a pair of side members pivoted to said supporting member and each provided with a portion extending upwardly from the points of pivotal connection of said side members with said supporting member and into proximity with said rail ends, and means located on the opposite sides of said pivots from the upstanding portions of said side members for forcing the upwardly extending portions of said side members towards the rails.

17. In a rail joint structure for connecting meeting rail ends, a supporting member underlying said rail ends, a pair of side

members pivoted to said supporting member and each provided with a portion extending upwardly and into proximity with the webs of the rails, and means carried by said side members and engaging portions of said supporting member for forcing the upwardly extending portions of said side members towards the rails and at the same time drawing said supporting member into closer contact with the under surfaces of said rail ends.

18. In a rail joint structure, the combination with meeting rail ends, of a supporting member underlying said meeting rail ends, side members hingedly connected to said supporting member, and means coacting between said side members and said supporting member for drawing the said supporting member upwardly into tensioned engagement with the under surfaces of said rail ends.

19. In a rail joint structure, the combination with meeting rail ends, of a supporting member underlying said meeting rail ends, side members hingedly connected to said supporting member and having portions extending upwardly upon opposite sides of said rail ends, and means coacting between said side members and said supporting member for forcing the upwardly extending portions of said side members into close engagement with opposite sides of said rail ends.

In testimony whereof I have affixed my signature.

JOHN W. CLARK.
